KNIFE OR THE LIKE

Marion Anderson Noyes, West Newbury, Mass.,
assignor to Towle Manufacturing Company,
Newburyport, Mass., a corporation of Massachusetts

Application October 7, 1952, Serial No. 21,745

Term of patent 14 years

(Cl. D22—3)

To all whom it may concern:

Be it known that I, Marion Anderson Noyes, a citizen of the United States of America, residing at West Newbury, county of Essex, and Commonwealth of Massachusetts, has invented a new, original, and ornamental Design for a Knife or the like, of which the following is a specification, reference being had to the accompanying drawing forming a part thereof.

Fig. 1 is a plan view of a knife showing my new design;

Fig. 2 is a cross section taken on the line 2—2 of Fig. 1;

Fig. 3 is a cross section taken on the line 3—3 of Fig. 1;

Fig. 4 is a cross section taken on the line 4—4 of Fig. 1; and

Fig. 5 is a cross section taken on the line 5—5 of Fig. 1.

While the design is illustrated applied to a knife it is to be understood that the design may be used on forks, spoons, or like articles without departing from the spirit of the invention.

I claim:

The ornamental design for a knife or the like, substantially as shown and described.

MARION ANDERSON NOYES.
